UNITED STATES PATENT OFFICE.

MARSHALL B. LLOYD, OF MENOMINEE, MICHIGAN, ASSIGNEE, BY MESNE ASSIGNMENTS, TO HEYWOOD-WAKEFIELD COMPANY, OF BOSTON, MASSACHUSETTS, A CORPORATION OF MASSACHUSETTS.

WALL COVERING.

Application filed June 5, 1920. Serial No. 386,830.

To all whom it may concern:

Be it known that I, MARSHALL B. LLOYD, a citizen of the United States, and a resident of Menominee, county of Menominee, 5 and State of Michigan, have invented certain new and useful Improvements in Wall Coverings, of which the following is a specification.

My invention relates generally to improvements in wall constructions and wall coverings.

In every room, and especially in the rooms of dwellings and other places of habitation, a considerable amount of dust is found. 15 This ordinarily settles upon the floor, and in the rugs, carpets or other floor coverings from which it is constantly being raised as the occupants move about. Some of this dust is deposited upon the walls where it is 20 difficult of removal and unsightly in appearance.

One of the objects of my invention is to provide a wall construction or covering which shall act as a dust collector in which 25 the dust shall remain hidden, until removed.

Another object of my invention is to provide a wall construction or covering which shall act to collect the dust and which shall be of such construction that the dust collected thereby can be very quickly, easily 30 and thoroughly removed.

It is also an object of my invention to provide a wall construction which shall aid in the circulation of air and in the proper 35 ventilation of the room.

Again there are many places in homes and other buildings where a paneled wall having a wall covering is desired. While one of the objects of such an arrangement is the 40 production of an artistic effect, another and quite as important an object, is the provision of a permanent or semi-permanent covering. Such a covering is much desired for the walls of vestibules, stairways, and also on 45 walls, generally, commencing at or near the floor and extending upwardly therefrom, above a line where it is likely to be rubbed or brushed by occupants or by household objects.

50 It is an object of my invention to provide a wall covering of a substantially permanent character, and a method of applying same whereby relative movement of the wall and covering, as when the wall cracks or settles,

may take place without injuring the wall 55 covering.

Again it is an object of my invention to provide a wall covering that can be affixed to the wall with a minimum number of fastening devices thereby better enabling 60 relative movement of the wall and covering to take place and also reducing the time required for the application thereof.

A further object of my invention is to provide a wall covering which can be produced in a relatively cheap manner; which can be applied quickly and easily; which shall be capable of being finished in a variety of ways to produce artistic effects and which shall be practically indestructible. 70

My invention consists, generally, in a wall construction and covering, whereby the above named objects, together with others that will appear hereinafter are attainable, and my invention will be more readily 75 understood by reference to the accompanying drawings which illustrate what I consider, at the present time, to be the preferred embodiment thereof.

In said drawings: 80

Fig. 1 is an elevation of a panel wall construction embodying my invention.

Fig. 2, is a section taken substantially on the line 2—2 of Fig. 1.

Fig. 3, is an enlarged section substantially 85 on the line 3—3 of Fig. 1.

Fig. 4, is an enlarged section, substantially on the line 4—4 of Fig. 1.

Fig. 5, is a detail face view of a portion of 90 wall covered with material embodying my invention;

Fig. 6, is a view substantially on the line 6—6 of Fig. 5.

Fig. 7, is a vertical sectional view of my 95 wall construction as designed to facilitate ventilation; and

Fig. 8 is a cross-sectional view taken substantially on the line 8—8 of Fig. 7.

Referring particularly to Fig. 1, 2 represents the base board of a wall and which is 100 shown simply to typify the environment. 3 represents vertical strips, and, 4, horizontal strips which are secured to the wall, 5, and which thereby divide it into a number of panels. 6, represents a wall covering which 105 may be of a size to cover several of the panels, but which preferably is of a size sufficient only for a single panel and which,

in fact, is partly held in place by the vertical and horizontal strips, 3, and 4, respectively, to be described in detail hereinafter.

As stated, in the opening of the specification, I aim to provide a wall covering which shall be of such a nature that the wall may come or go, i. e., crack or settle without affecting the covering. To this end, I provide a covering which while somewhat flexible, is nevertheless, in a sense, self-supporting. The material which I prefer to use is a woven product composed of spaced supports or stakes, 7, over and under which filler strands, 8, are woven. This material may be formed of different products, but one very suitable product is paper which is twisted and properly sized and which is commonly known as fibre reed. Natural reed may also be used, but is usually less desirable than fibre reed for the reason that it is likely, especially in dry atmospheres, to chip and crack whereas the fibre reed is of a much more flexible and less easily broken nature. The stakes 7 may be likewise formed of twisted paper, or of reed or other material, but, because of the requirements for a wall covering, I prefer to form the stake with a metal core 7' around which the paper is twisted. The resulting stakes, therefore, correspond somewhat to a beam and acts as a support for the filler strands. That is to say, the stakes, while bendable, are, at the same time, sufficiently rigid to be self supporting in workable lengths, as against collapse even though placed in a vertical position and when carrying a large number of filler strands. The wall covering may be woven either by the hand, or by machines which I have designed for this purpose, and it is usually formed in sizes sufficient to cover a number of panels and then cut into the pieces of such size as to correspond to the size of the panel in which it is to be placed. When the material is cut ready for application to the panel, it contains a large number of loose ends 9 (see Fig. 5) which are unsightly and which, unless confined, would permit of the fabric unraveling. I confine the end portions of the fabric and, at the same time, hide them by undercutting the strips 3 and 4, as indicated at 10 and 11, respectively, in Figs. 2, 3, and 4. The cut-away portion of the strips 3 and 4 is just sufficient snugly to accommodate the material between the outer surface of the wall and the adjacent part of the strip. The panel of material, 6, is thus held along four of its edges which confinement is practically sufficient to hold the panel in place because of the characteristics of the stake and strand material before described. It will be observed that, as here shown, no fastening devices pass through the strips and fabric thereby enabling the relative movement of the wall, covering, and strips as may be

necessary from time to time to accommodate relative expansion of the different parts or even to accommodate severe settling or cracking of the wall.

As a factor of safety, I prefer, additionally, to hold the wall covering in place as by means of a few staples 12 which may be distributed in desired spaced relation throughout the wall covering. In the application of these staples, I pry one of the filler strands upwardly or downwardly at that point and then drive the staple over the stake as is well shown in Fig. 6. Thereafter the displaced filler strand is moved back to its proper position at which time it passes over the staple thereby hiding it and forming a blind fastener. By fastening the covering material in this manner, its beauty as a woven material remains unimpaired and it can be painted, tinted, or otherwise finished in any desired manner. It should be understood that the staples 12 do not so secure the covering to the wall as to prevent the relative movement of wall and covering, before described, for the staple can very readily move upwardly or downwardly upon the stake. In the first place, it may move practically the thickness of the filler strand before engaging any of the filler strands and then even further movement may be permitted by a slight shifting of the adjacent filler strands. Such extreme movement, however, would hardly be encountered in practice.

It will be noted that the surface of the wall may, if it is a plaster wall, be left with a rough finish, as indicated at 13 in Figs. 2 and 6, thus eliminating the necessity of applying the usual smoothing or finish coat of plaster. While the stakes are shown in the drawings, as being vertically positioned, and while this generally is the preferable position they may, if so desired, be horizontally disposed, in which event the filler strands would occupy a vertical position. In either event, they act as beams supporting the filler strands and resulting in a relatively non-collapsible though flexible fabric which, when applied as a wall covering in the manner stated, overcomes many of the objections inherent in semi-permanent or permanent wall coverings heretofore devised. Because of the lack of a better term for the means of fastening the covering material to the wall in such manner as to permit relative movement of the parts, I shall hereinafter refer thereto as a yieldable fastening or as yieldably holding the covering against the wall.

In addition to providing a flexible construction, the many strands of the woven fabric, which provide a relatively open weave, act admirably as a dust collector, for as the air circulates the dust particles are entrapped by the strands thus freeing

the air of such particles. Therefore, instead of depositing the dust upon the floor where it would constantly be raised, as in walking, the dust is collected upon the wall 5 surface which is not subjected to such action and which, therefore, acts to clarify the air. Because of the character of the covering, a considerable amount of dust can be collected without becoming unsightly. The 10 wall covering, as before stated, is flexibly secured to the wall which fact greatly facilitates the removal of the dust therefrom. Removal can be very easily accomplished by the use of a vacuum cleaner. As the 15 vacuum cleaner passes over the wall surface, the wall covering, due to its flexible construction, is set into vibration so that it acts quickly to loosen and shake the dust therefrom so that it may be readily withdrawn by the vacuum device. Obviously, because of the open character of the weaving, a sufficient volume of air can flow in 20 and behind the strands to enable the proper functioning of the vacuum cleaner.

25 In Figs. 7 and 8 I have illustrated a wall which is constructed of covering material such as converts the wall into a ventilating element. This construction, while not in any sense limited thereto, is especially applicable to the construction of summer homes. In said figures 20 represents the floor, 21 the ceiling, and 22 uprights to which the wall covering is to be secured. These uprights may be formed of two-by- 35 fours and braced in the usual or desired manner. On opposite sides, the wall covering material 23 and 24 is provided. This covering material may be secured directly to the uprights 22 as by staples or other fastening devices. The wall covers 23 and 40 24 are preferably composed of the stake and strand fabric already described with reference to Figs. 1 to 6. This construction in effect provides a number of vertical ducts 45 through which air entering from the adjoining rooms may pass upwardly into the attic or other space 26 above. Because of the open character of the wall covering, the air may pass freely therethrough resulting 50 in a marked increase in air circulation and hence providing a construction which is especially desirable. The desirable characteristics of the dust collecting and removal are present in this construction as 55 in the other form previously described.

I claim:

1. The herein described improvements in wall covering constructions, embodying therein a wall; a finishing covering therefor composed of a plurality of spaced stakes which in workable lengths have sufficient rigidity to be self-supporting and to resist forces tending to bend abruptly, and filler strands woven over and under said stakes in 60 side by side contacting relation and being

carried thereby; and means yieldably holding said covering against said wall.

2. The herein described improvements in wall covering constructions, embodying therein a wall; a finishing covering therefor composed of a plurality of spaced vertically positioned stakes which in workable lengths have sufficient rigidity to be self-supporting and to resist forces tending to bend abruptly, and horizontally disposed filler 70 strands woven over and under said stakes in side by side contacting relation and being carried thereby; and means yieldably holding said covering against said wall.

3. The herein described improvements in wall covering constructions embodying therein a wall; a finishing covering therefor composed of a plurality of spaced stakes, composed at least in part of wire, and which in workable lengths have sufficient rigidity 80 to be self-supporting and to resist forces tending to bend abruptly, filler strands woven over and under said stakes in side by side contacting relation and being carried 85 thereby; and means yieldably holding said covering against said wall.

4. The herein described improvements in wall covering constructions, embodying therein a wall, a covering therefor composed of a plurality of spaced stakes which in workable lengths have sufficient rigidity to be self-supporting and to resist forces tending to bend abruptly, and filler strands woven over and under said stakes in side 90 by side contacting relation and carried thereby; and means yieldably holding said covering against said wall, said means including strips secured to the wall and having overhanging flange portions between 95 which and the wall, the edge portions of 100 the fabric are secured.

5. The herein described improvements in wall covering constructions, embodying therein a wall; a covering therefor composed of a plurality of spaced stakes which in workable lengths have sufficient rigidity to be self-supporting and to resist forces tending to bend abruptly, and filler strands woven over and under said stakes and being 110 carried thereby; and means yieldably holding said covering against said wall, said means including fastening devices entering 115 the wall, engaging part of the covering material and being hidden from view by other portions thereof.

6. The herein described improvements in wall covering constructions, embodying therein a wall; a covering therefor, composed of a plurality of spaced stakes which in workable lengths have sufficient rigidity to be self-supporting and to resist forces tending to bend abruptly, and filler strands woven over and under said stakes and being 120 carried thereby; and means yieldably holding 125 said covering against said wall, said 130

means including fastening devices which slidably embrace the stakes and which are rigidly embedded in the wall.

7. The herein described improvements in wall covering constructions, embodying therein a wall; a covering therefor composed of a plurality of spaced stakes which in workable lengths have sufficient rigidity to be self-supporting and to resist forces tending to bend abruptly, and filler strands woven over and under said stakes in side by side contacting relation and carried thereby; and means yieldably holding said covering against said wall, said means including fastening devices embracing the stakes under the filler strands, and being rigidly embedded in the wall.
8. The herein described dust collecting wall covering construction embodying therein a wall, a covering therefor composed of spaced stakes and filler strands woven over and under said stakes, and means for holding said covering against said wall.

9. The herein described dust collecting wall covering construction embodying therein a wall, a covering therefor composed of spaced stakes and filler strands woven over and under said stakes, and means for flexibly holding said covering against said wall.

10. The herein described ventilating wall construction embodying therein wall framing members, and a covering secured thereto said covering being composed of spaced stakes and filler strands woven over and under said stakes.

11. The herein described improvements in wall constructions embodying therein a wall; a covering therefor composed of a plurality of relatively rigid stakes, and filler strands having rounded portions, which filler strands are woven over and under stakes and being carried thereby; and means for holding said covering against said wall.

In testimony whereof, I have hereunto set my hand, this 8th day of April, 1920.

MARSHALL B. LLOYD.
